WILLIAM C. SOLE, OF SULLIVAN, INDIANA.

PITMAN FOR DRILLING-MACHINES.

1,245,051.

Specification of Letters Patent. Patented Oct. 30, 1917.

Application filed February 8, 1917. Serial No. 147,275.

To all whom it may concern:

Be it known that I, WILLIAM C. SOLE, a citizen of the United States, and a resident of Sullivan, in the county of Sullivan and State of Indiana, have invented a new and Improved Pitman for Drilling-Machines, of which the following is a full, clear, and exact description.

This invention relates to deep well drilling machines and has particular reference to the pitman connection between the power shaft crank and the walking beam.

In the practice of deep well drilling machines, a common source of serious difficulty lies in the want of suitable resiliency or cushioning means between the power and the walking beam connections. It must be borne in mind that the string of tools and the means for suspending the same in a deep hole are very heavy, and therefore the power devices must be very strong to effect the normal operation of the device, to say nothing of the unusual strains that are incident to the sticking of the tools in the hole. Various expedients have been resorted to for providing means to relieve the shocks incident to the operation of these machines, so as to prevent breakage of the connections or straining of the power shaft or the like.

Among the objects of this present improvement therefore is to provide a pitman having a construction which may be termed telescopic and which includes a spring having length and compressibility enough to allow the crank to make a complete rotation in case the tools stick in the hole, thereby preventing breakage of the connections or the breaking or bending of the power shaft. Said spring also has sufficient rigidity or strength to provide for the normal operation of the walking beam.

Another object of the invention is to provide improved facilities for connecting the end of the pitman to the band wheel crank, whereby the same may be disconnected readily for the purpose of renewing the bearings or other purposes.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like

reference characters designate the same parts in the several views, and in which—

Figure 1 is a side elevation of my invention, shown applied to one end of a walking beam and the power crank;

Fig. 2 is a front elevation of the same with the walking beam omitted;

Fig. 3 is an enlarged side elevation of the lower end of the pitman, parts being in section; and

Fig. 4 is a view at right angles to Fig. 3 and with the parts in the same relative position.

Referring now more particularly to the drawings, I show at 10 a walking beam adapted to be oscillated from any well known power or band wheel 11, having an axle 12 and crank 13. A wrist pin 14 is adjustably connected in any one of the series of holes 15 in the free end of the crank.

The improved form of pitman comprises a stirrup 16 secured to the end of the walking beam in the usual manner and attached by means of bolts 17, or their equivalent, to the upper end of a tubular member or cylinder 18, having formed in its opposite sides a pair of longitudinal slots 19. A cap 20 is rigidly secured to the lower end of the tube 18 and is provided with a central hole 20' therethrough.

Another main portion of the pitman comprises a plunger 21 formed upon or secured in any suitable manner to the head or body 22, which may be of rectangular form in cross section or provided with flat faces. Said plunger projects upwardly through the hole 20' of the cap and the upper or free end of the plunger is screw threaded for co-operation with a nut or runner 23, preferably of a form to fit within the interior of the tube 18, but provided with lugs 24 which project outwardly through the slots 19, whereby the runner is held from rotation. A powerful master spring 25 surrounds the plunger between the runner at one end and the cap 20 at the other end.

This spring is powerful enough to transmit the power from the shaft 12 and crank 13 to the walking beam for the usual operation, but is sufficiently resilient to cushion all impacts or irregularities in the operation of the machine. Furthermore, the spring and plunger are long enough and the slots 19 provide for sufficient reciprocation of the runner to allow the crank 13 to make a complete rotation in case the drilling bit or any

other portion of the tools become stuck, so that the danger of breakage or twisting of the power shaft is practically eliminated. Since the tube 18 is held from rotation by means of the stirrup 16 the adjustment of the runner with respect to the plunger may be effected readily by rotation of the head and plunger while the runner is held from rotation by the tube. The cap end of the tube 18 is adapted to move more or less freely toward and from the head 22.

The third main portion of the pitman comprises a strap portion consisting of two parallel straps or plates 26 articulated or jointed to the head 22 by means of a strong pivot pin or bolt 27 and around which pivot the lower end of the pitman is adapted to swing freely in one direction, namely, away from the crank, but is limited in its movement in the other direction by means of a square shoulder 28 adapted to coöperate with the cap 20. As an additional means, however, to make the pitman as a whole rigid, or prevent the relative movement of the strap portion 26 laterally with respect to the head 22 and tube 18, I provide a locking pin 29 arranged between the two straps 26 and adapted to be projected at its upper end into a socket 30 formed in the lower end of the head 22. Said pin 29 is guided in a pair of cross pieces or guides 31 and 32 which serve also as stiffeners or braces for the straps. A spring 33 acts upon the pin at one end tending to force it into the socket 30 while the other end of the spring bears against the guide 32. A link 34 is pivoted at 35 to the lower end of the pin.

The bearings for the wrist pin 14 consist of two members or boxes 36 and 37 fitted between the lower ends of the straps 26. The fixed bearing 36 is supported upon a plate block 38 secured in place by a pair of bolts 39 which serve also as a means to prevent the spreading of the plates or straps 26. The other bearing 37 has secured to it or formed upon it, a shank 40 which is guided through a transverse brace or guide 41 similar to the guide 32 above described, and a spring 42 surrounds this shank and acts between the bearing at one end and the guide 41 at the other end. The action of the spring tends to hold the movable bearing 37 down against the fixed bearing and in contact with the wrist pin. To the upper end of the shank 40 is pivoted at 43, a link 44 of the same character as the link 34.

45 indicates a transverse bolt or pivot rod extending between and through the straps 26 about half-way between the braces or guides 32 and 41. A lever 46 is pivoted centrally upon this pivot rod 45 and is held centered thereon by means of sleeves 47. The links 34 and 44 are pivoted respectively at the points 34' and 44' upon the lever 46 at equal distances from the axis of the pivot

rod 45. The lever and links are so formed that when the free end of the lever is swung down, as shown in Figs. 3 and 4, the link 34 and pin 29 are drawn down against the force of the spring 33, said pin thus being withdrawn from the socket 30, and at the same time the shank 40 and movable bearing 37 are drawn upwardly against the force of the spring 42. The pivot points 34' and 44', however, of the links pass the dead center or beyond the lines joining the axis of the pivot rod 45 and the respective points of connection between the links and the pins, whereby the parts will be automatically locked and held in the position indicated in Fig. 3. The bearings being thus separated and the locking pin 29 being withdrawn from the rigid head 22, it is easy for the strap portion of the pitman to be swung laterally, as shown in dotted lines in Fig. 2 for the purpose of disconnection from the wrist pin. The main bearing 36, or the one which is subjected to the major portion of the service may then be easily removed or replaced by a new one by simply removing the bolts 39 and allowing the plate 38 and bearing 36 to be slipped off or beyond the lower ends of the straps. When the parts are again assembled and the pitman connected to the wrist pin, a simple reverse or upward movement of the lever 46 permits the springs 33 and 42 to snap the parts back to their normal position where they will be firmly held by the springs. The free end of the lever 46 will thus be carried well up toward or between the straps 36.

I claim:

1. In a pitman, the combination of a tubular member having a cap secured to its lower end and being provided in its opposite sides with parallel longitudinal slots, a rigid head at the lower end of the tubular member, a plunger connected to the head and extended through the cap and into the tubular member, the upper end of the plunger being threaded, a runner coöperating with the threaded portion of the plunger and having lugs projecting into said slots to prevent rotation thereof while the head and plunger may be rotated, a powerful spring surrounding the plunger within the lower end of the tubular member between said cap and said runner and serving to hold the head close to the cap, a lower end connecting member pivoted to said head and adapted to swing laterally from the general direction of the axis of the pitman so as to facilitate the adjustment of the plunger with respect to the tubular member, and means acting between the connecting member and said head to lock the same in alignment.

2. In a pitman, the combination with a main upper portion including a rigid head having a socket in its lower end, a lower end

connecting member including a pair of bearings, one of the bearings being movable upwardly from the other, a locking member carried by the latter mentioned member and 5 coöperating with said socket to hold the parts in rigid alinement, and lever devices connected to said locking member and said movable bearing to move them both toward each other to facilitate the disconnection of 10 the pitman from the power devices.

3. In a pitman, the combination of a main upper portion including a rigid head, a lower end connecting member, means pivot-

ally connecting the connecting member to the head providing for lateral movement of 15 the connecting member, a locking member carried by the connecting member and movable longitudinally thereof into coöperation with the head to lock the two main parts in rigid alinement, a spring acting upon the locking member to hold it in locking position, and lever connections with said locking member serving to withdraw it from locking position and automatically hold it so withdrawn.

WILLIAM C. SOLE.
